United States Patent Office

Des. 208,826

Patented Oct. 3, 1967

208,826

DISPENSING BOTTLE

Fred E. Hutton, Santa Monica, Calif., assignor to
James U. Stewart, La Habra, Calif.

Filed June 7, 1966, Ser. No. 2,595

Term of patent 14 years

(Cl. D58—6)

FIG. 1 is a front isometric view of a dispensing bottle showing my new design;

FIG. 2 is a side elevational view, the opposite side being a mirror image of the side shown;

FIG. 3 is a front elevational view;

FIG. 4 is a rear elevational view;

FIG. 5 is a bottom plan view; and

FIG. 6 is a top plan view thereof.

I claim:

The ornamental design for a dispensing bottle, substantially as shown and described.
